UNITED STATES PATENT OFFICE.

THOMAS RHODUS, OF CHICAGO, ILLINOIS, ASSIGNOR TO THE MAGNPHONE COMPANY,
A CORPORATION OF ARIZONA.

ELECTRICAL CONNECTOR.

1,282,630.

Specification of Letters Patent. Patented Oct. 22, 1918.

Application filed July 9, 1917. Serial No. 179,814.

To all whom it may concern:

Be it known that I, THOMAS RHODUS, a citizen of the United States of America, and a resident of Chicago, in the county of Cook, State of Illinois, have invented certain new and useful Improvements in Electrical Connectors, of which the following is a specification.

This invention relates to that class of electrical connectors adapted for the attachment of line wires to the terminal posts of primary batteries, and has for its object:

To provide a simple and efficient structural formation of a connecting block having permanent attachment to a line wire and adapted for connection in a readily detachable manner to the varied forms of terminal stems or posts of primary batteries of different makes, all as will hereinafter more fully appear, in the accompanying drawing:

Figure 1 is an elevation of a primary battery having the present improvement applied.

Fig. 2 is a top view of the connector block. Fig. 3, is a perspective view of the same.

Fig. 4, is a section on line $x-x$, Fig. 2.

Similar reference numerals indicate like parts in the several views.

Referring to the drawing, 1 designates a primary electric battery having the usual terminal poles or stems 2, 3 adapting the same for connection with the usual line wires 4, 5 by connecting means as follows:

6 designates a connecting block of a cylindrical or other suitable form, individual to a line wire aforesaid, and formed with a socket or recess 7 for the reception of one end of the said line wire, the connection being made permanent preferably by the usual soldering operation.

8 designates an orifice of an approximately round form extending preferably through the block 1 in preferably parallel relation to the aforesaid socket or recess 7, and adapted to receive a terminal stem 3 of the battery, when said stem is of a round or approximately round form.

9 designates a companion orifice or passage of an elongated form and preferably opening through the side of the block 6 as shown. In the present invention the orifice or passage 9 is preferably arranged to intersect or open into orifice 8 aforesaid, and is adapted to receive a terminal stem 2 of the battery, when said stem is of a flat plate form.

10 designates a clamping screw having screw-threaded engagement in a lateral orifice in the connecting block 6. Said orifice 60 opens in common into the above described orifices 8 and 9, so that the clamping screw 10 is adapted to have holding engagement with a battery stem 2 or 3, occupying either orifice 8 if round, or orifice 9, if otherwise, to 65 firmly clamp the parts together and maintain the same in electrical contact.

Having thus fully described my said invention, what I claim as new and desire to secure by Letters Patent, is:

1. An electrical connector comprising, a block adapted for permanent connection to a line wire and formed with an approximately round orifice and an elongated orifice arranged in intersecting relation, and a 75 clamping screw common to both of said orifices, substantially as set forth.

2. An electrical connector comprising a block formed with a socket recess for permanent connection to a line wire and with 80 an approximately round orifice and an elongated orifice arranged in intersecting relation, and a clamping screw common to both of said orifices, substantially as set forth.

3. An electrical connector comprising a block adapted for connection to a line wire and formed with an approximately round orifices and an elongated recess, and a clamping screw common to said orifice and said 90 recess, substantially as set forth.

Signed at Chicago, Illinois, this 7th day of July, 1917.

THOMAS RHODUS.
